METAL WALL BUILDING CONSTRUCTION

George Vincent Palmer, Los Angeles, Calif., assignor to Palmer Steel Buildings, Incorporated, Los Angeles, Calif., a corporation of California

Application September 6, 1933, Serial No. 688,307

17 Claims. (Cl. 189—1)

This invention relates to a novel form of building construction and particularly to a construction embodying the use of a plurality of sectional preformed metal wall elements brought together in an advantageous relationship.

5 The principal object of the present invention is to provide a construction employing preformed structural metal shapes in a building construction whereby a highly advantageous structure from the standpoint of cost, strength and appearance, and ease of assembly, is obtained, which is weather-tight, insect-proof and resistant to damage by the elements or by animal or vegetable agencies.

10 15 The present invention involves the use of structural shapes which are commercially available or may be readily produced at low cost, and which may be assembled in a novel and advantageous manner to form walls and wall sections as well as to provide a complete building structure, and 20 also involves certain advantageous means whereby correlated structural elements may be secured to such walls or wall surfaces. Structural shapes such as shown and described in U. S. Patent No. 1,867,433, issued to J. H. Young, July 12, 1932, 25 may be used to good advantage for the purposes of this invention, but it will be understood that other types of preformed metal wall elements, examples of which are described hereinafter, may 30 also be used.

35 One of the principal objects of the invention is to provide a building construction in which a plurality of cellular metal structural elements are assembled to form a unitary wall structure, either with or without the use of non-cellular wall elements.

40 A further object of the invention is to provide a composite metal wall structure formed of a plurality of preformed metal structural shapes in which the necessary load-bearing strength is provided by structural shapes having one or more hollow cellular members closed in cross-section and other portions of said structure are provided with spacing or filler elements interlocked with the load-bearing elements whereby a composite wall structure having the desired load-bearing properties is obtained at a low cost.

45 50 A further object of the invention is to provide a building construction in which certain load-bearing portions thereof are provided by cellular preformed metal structural shapes cooperating with a concrete or other masonry structure.

55 A further object of the invention is to provide a building construction in which corners, recesses, reveals, and other wall sections are obtained

through the use of preformed metal elements having a cellular structure and provided with suitable perforations through which reinforcing mediums such as steel rods, concrete, or the like may be passed in a load-bearing relation to impart load-sustaining characteristics to such elements. 5

A further object of the invention is to provide a building construction in which one or more perforated cellular wall elements are associated in alined relationship and interlocked in load-transmitting relation through the agency of reinforcing members extending through the perforations in said elements.

A further object of the invention is to provide 15 a cellular metal wall construction having means for circulation of air within the wall structure for cooling or ventilating the same.

A further object of the invention is to provide a metal wall construction formed of one or more 20 cellular preformed metal elements to which suitable reinforcing elements may be secured for the purpose of providing structural attachment between such wall structure and other contiguous building structures, for example, in the attachment 25 of a ceiling or floor structure to a wall structure.

The construction of the present invention contemplates the use of structural elements formed 30 of sheet steel or other metal, and consisting generally of flat plates provided or not with one or more hollow cells secured thereto and extending longitudinally thereof, said flat plate portions of the structural elements being preferably provided at their longitudinal edges with overlapping portions, whereby two or more of said elements may be assembled in a plane. The overlapping portions may, if desired, be so formed as 35

to interlock with one another so as to form, when so assembled, a substantially continuous weather-resistant structural wall of high load-carrying and stress-resisting capacity. In the forming 40 of a wall through the use of structural elements of the character above-described, the several elements are preferably disposed in an alined vertical relation and the upper ends of the several elements securely fastened as by welding or otherwise to a suitable transverse load-distributing member and the lower ends secured in a suitable 45 manner to a structural member extending along the horizontal length of such wall.

The above-mentioned structural elements are 50 preferably provided, particularly where such elements are to be used in load-bearing relation, with longitudinally extending hollow cells which 55

are substantially closed in cross-section whereby a rigid column construction is obtained, and the preferred embodiment of the invention contemplates the provision of suitable perforations in the side walls of these cellular portions of the elements through which a suitable reinforcing medium may be extended, or through which service conduits or the like may be passed substantially horizontally through and in the plane of the wall. The invention also contemplates a construction in which the aforementioned hollow cells are provided with suitable perforations in their walls through which air may be drawn from points exterior of the wall structure and circulated vertically through the cells and transversely from one cell to another.

The invention also contemplates the provision of suitable perforations in the side walls of the aforementioned hollow cells through which a suitable reinforcing medium may be extended in load-transmitting relation to the wall element whereby conjunctive structural elements of the building such as a floor or any other divergent structural element may be interlocked with such wall structure.

The attached drawings show various features of the present invention, together with important modifications thereof, and referring thereto:

Fig. 1 is an isometric view of a composite metal wall of the present invention, showing the use of several different types of wall elements;

Fig. 2 is a horizontal sectional view of several types of wall elements, showing a manner of assembling the same into a unitary wall structure;

Fig. 3 is a view corresponding to Fig. 2, showing a combination of single cell elements with plane spacing or filler elements;

Figs. 4, 5, and 6 show various forms of corner construction according to the present invention in which joining wall structures are inter-secured as by means of welding or the like.

Figs. 7, 8, 8a, and 9 show alternative corner constructions in which joining wall structures are inter-secured through the agency of cooperating reinforcing members;

Fig. 10 is an isometric elevation showing the attachment of surface coating material to a wall structure according to the present invention;

Fig. 11 is a sectional view thereof taken on line 11-11 in Fig. 10;

Fig. 12 is an isometric view showing a metal structural element according to the present invention provided with suitable perforations to facilitate circulatory air movement within the cellular portions thereof;

Fig. 13 is an isometric view showing the manner in which a ceiling or floor beam or other transversely extending member may be attached to a wall section in load-bearing relation according to the present invention;

Fig. 14 is a view corresponding to Fig. 13 showing a manner in which a transverse member may be positioned with respect to the wall structure in which the load-bearing characteristics thereof are improved by the use of a masonry interlock;

Fig. 15 shows the manner in which a divergent masonry structural member may be secured to a wall section in load-bearing relation and also shows means whereby a wall section may be ventilated by air circulation within the wall.

Fig. 16 shows an arrangement whereby wall elements may be joined to a masonry column or the like in stress-communicating relation thereto and also showing the manner in which a window lintel

may be formed and service conduits extended through the several wall elements;

Fig. 17 is a view corresponding generally to Fig. 16 showing an alternative method for securing the metal wall sections to a masonry structure in stress-transmitting relation;

Fig. 18 is an isometric view of a building construction, showing the manner in which constructional features of this invention may be associated.

Referring to the drawings. Figs. 1 to 3 show the general construction of the preformed metal wall elements and the manner in which said elements may be disposed in contiguous aligned relationship to form an extended wall structure.

In Fig. 1 I have shown three types of cellular wall elements designated at 1, 2 and 3, the element 1 comprising a flat plate 11 provided at its longitudinal edges with suitable male and female interlocking means such as a flange 12 at 20 one edge and a channel 13 at the other edge.

Secured to said plate 11 in some suitable manner, as by welding, a bent plate 14 is provided at one side of the plate, forming a channel of "U" or "V" shape and defining with the plate a hollow cell C 25

of closed cross section having the cross-sectional shape of a symmetrical trapezium, the forward and rearward parallel walls of said trapezium being defined, respectively, by the plate 11 and the portion 14' of the bent plate 14, and the non-

parallel side walls of the trapezium being defined by the portions 14" of the bent plate 14. In this particular form of wall element the cell C is disposed adjacent the edge of the plate 11 having the female interlocking member 13, but it

will be appreciated that a similar form of element may be provided in which the cell C extends along the edge of the plate having the male interlocking member 12, according to the particular requirements of the installation. If desired, the plate 11 may be reduced in width, so as to provide a single cell element in which the cell occupies substantially the full width of the plate.

The form of wall element shown at 2 differs 45 from the form shown at 1 in having two adjacent cells C preferably formed from a single sheet 14a and each comparable to the cell shown in connection with the element 1. This latter form of element is structurally more rigid than the element 1 due to the provision of two adjacent cells and is particularly useful where the wall section is to be subjected to considerable vertical load, as hereinafter described. The section 3 is comparable to the section 1 in that it is provided

with a single cell C of less width than the plate but, this cell is shown disposed substantially medially of the plate 11 instead of adjacent one edge thereof.

Under some conditions I have found it preferable to space the load-bearing wall elements, such as the elements 1, 2 or 3 with one or more spacing or filler elements such as shown at 15, to obtain an extended wall structure of low cost and to provide for recesses, reveals, corner assemblies or the like, it being understood that cellular elements of the proper cross-sectional shape will be provided in the wall structure at such points as are subjected to vertical loads exceeding the load sustaining capability of the 70 filler elements 15.

In Fig. 2 I have shown several alternative forms of wall elements which differ in cross-sectional shape from those shown in Fig. 1. The elements

shown at 4 may be formed of two bent plates 16

and 17 providing cells C₁ which are of relatively great transverse depth. This type of element is particularly adaptable where a heavy wall section or a relatively thicker wall is desirable, and 5 in conjunction with other structural elements to form arches, reveals or the like. The type of element shown at 5 is quite comparable to that shown at 4 but is shown as provided with cells C₂ of relatively small transverse depth. The type 10 of element shown at 6 is a modification in which the cells C₃ are distorted to provide a modified cross-sectional area. The above-described elements are shown as assembled in a composite wall structure together with an element of the type 15 shown at 2 and with flat plates 15, all of said elements being provided with interlocking means 12 and 13 whereby said elements are assembled to form the composite structure. It will be appreciated that in any of the hereinabove described wall structures, individual wall elements of the desired cross-sectional configuration will be selected according to the load sustaining or other requirements of various portions of the wall structure.

20 Fig. 3 shows a light-weight wall structure provided through the use of cellular wall elements such as shown at 1, 2 and 3 assembled in spaced relation through the agency of intermediate flat plates 15.

25 Throughout the present specification and claims, wherein the side walls of the cells are mentioned, particularly in connection with perforations therein as will be subsequently described, it will be understood that these side walls refer to side walls such as are designated at 14" 30 in connection with the form of wall element shown at 2, irrespective of whether the element in question be of the type shown at 1, 2, 3, 4, 5 or 6.

35 In the above figures, the side walls of the several hollow cells are shown as provided with perforations 18 spaced at intervals along the length thereof through which a reinforcing medium may be passed according to one of the important objects of the invention. These perforations will 40 be more fully described hereinafter with relation to the manner of employing the same.

45 Figs. 4, 5 and 6 show constructions in which two joining wall structures may be intersecured at their junction, in which various types of wall 50 elements are employed. In Fig. 4 I have shown a wall 21 meeting a wall 22, the end element of the wall 21 comprising a flat plate element 15 and the end element of the wall 22 comprising a cellular wall element 2. The two wall structures 55 are brought into their correct relation and may be welded together as shown at 23 or otherwise secured to provide a unitary construction. In Fig. 60 5 I have shown a wall 24, having an edge element of the general type shown at 1 intersecting a wall 25 formed of a plurality of elements of the type shown at 2 and secured thereto by welding as at 26 or in any other suitable manner. In Fig. 65 6 I have shown a method in which the construction shown in Fig. 4 may be modified so that the wall 21 may be made to extend both sides of the wall 22, by welding the element 2 of the wall 22 to the plate 15 as at 27 or by securing the same in any other suitable manner in position to permit interlocking, through the agency of the 70 means 12 and 13, of a suitable element such as of the type shown at 2 to the plate 15 adjacent the junction of the walls 21 and 22.

75 In Figs. 7, 8, 8a and 9 I have shown certain wall junctions in which the walls are joined through the agency of reinforcing members ex-

tending through the perforations 18 in the cell walls and through suitable apertures at other advantageous locations in the several wall elements. Figs. 7, 8 and 9 are respectively comparable to Figs. 4, 5 and 6 above-described and, 5 referring particularly to Fig. 7, the plate 15 is provided with a suitable aperture 28 in line with the perforations 18 in the cell side walls 14" of the element 2 and a bolt 29 is passed through the aligned perforations and secured as by means 10 of nut 30 to securely position the joining walls 21 and 22. In a construction of this general type, I prefer to have the bolt 29 of such size as to fit quite snugly within the openings 18 and 28, so that a minimum of side-play is permitted. Furthermore, I prefer to use a wedge-shaped washer or the like, 30a, adjacent the nut 30 whereby said nut may be properly tightened against the inclined side wall 14".

20 In Fig. 8 I have shown the wall 24 secured to the wall 25 through the agency of a reinforcing rod 31 extending through the perforations 18 in the opposing cells of the adjoining elements 2 and through a suitably positioned aperture 32 in the edge element 1 of the wall 24. Concrete or other suitable material may be poured into the opposing cells of the wall 25 as at 33 and in the space therebetween as at 33', embedding the rod 31 and the adjacent portion of the plate 11 of the 25 edge element of the wall 24, suitable forms being provided as at 34 if desired during the pouring of the concrete. This construction provides a mechanical interlock of joining walls, of very high structural strength and load-bearing stress- 30 communication characteristics.

35 Fig. 8a shows a modification of the construction shown in Fig. 8, wherein a wall 53 provided with an element 2 at its end, is joined to a wall 54 which may be formed of one or more elements 2 having an element of the type shown at 40 1 positioned at the junction of the two walls. In this construction, suitable apertures or perforations are provided in the forward and rearward cell walls, as at 55 and 56, respectively, 45 in line with the openings 18 in the cells of the elements forming the wall 54, and a suitable reinforcing rod or the like 57 is extended through the aligned openings. Concrete or other suitable masonry is then poured into the adjacent cells, 50 as at 58, and into the junction area as at 58a, suitable forms being provided as shown in dotted lines at 59 until the masonry has solidified.

55 In Fig. 9, the walls 22 and 21 are secured in the manner shown in Fig. 7, and if desired this construction may be made stronger by disposing a form in some such position as shown in dotted lines at 34' and pouring concrete or other material into the space 35 and the end cell 36 of the wall 22. It will be appreciated that this 60 same reinforced construction may be provided for the arrangement shown in Fig. 7 if desired.

65 Figs. 10 and 11 show a method whereby surfacing materials such as plaster or stucco may be attached to the elements forming a wall structure, and referring thereto, a wall element of the type shown at 2 may be provided with a plurality of perforations 37 extending through the plate 11 into the cells C, and a plurality of perforations 38 in the rearward cell surface 14'. Either 70 the plate surfaces of the elements 2 may form the exterior of the wall or such exterior surface may be defined by the plane of the rearward cell surfaces 14'. The forward surface of the plate 11 may be given a coating 40 of a suitable stucco or 75

a plastering material such as an emulsified plastic composition, of suitable nature, in which use the surfacing material will be locked to the plate by extending through the perforations 37 as shown at 37a. The cell side of the wall structures may be provided with a surface coating by attaching metal lath or the like 41 thereto through the agency of suitable fastening means such as, for example, spring-wire staples as shown at 42, extending through the perforations 38 and engaging the rear cell wall 14' after the manner shown. The perforations 37 and 38 may be formed in the wall elements during the fabrication thereof in the factory or may be punched, drilled, or otherwise provided in the structure during or after assembly thereof, in any well known manner. If desired, a plaster-supporting material such as "button-lath" may be secured to either the plate or cell side of the wall elements as by means of 20 suitable nails such as the so-called "concrete stub-nails" which are sturdy enough to be driven through the metal forming the cell wall or the plate 11, and plaster may then be applied directly to the plaster-supporting material.

Fig. 12 shows a typical wall element of the type shown at 2, provided with one or more hollow cells C, and formed into a wall structure in which the lower end of the wall element is suitably secured to a supporting member such as a masonry structure 45 and preferably embedded therein. The form of wall element shown is provided with a plurality of openings 18 in the cell side walls and the forward surface defined by the plate 11 of the element 2 is shown as provided with an exterior coating of suitable material as at 46 and an interior surface coating 46'. An opening 47 is provided adjacent the lower end of cell C extending through the plate 11 and the coating 46, by means of a nipple 47a or the like, for admission of atmospheric air to said cell. This construction provides for admission of circulating air which, if the wall structure be heated by exposure to sunlight or the like, will pass upwardly through the flues afforded by the several cells C and thus establish circulation by convection, suitable apertures being provided at some point adjacent the upper end of the wall element for exit of the circulatory air. In this figure the several arrows indicate the air circulation and it will be seen that cross-circulation will be provided through the openings 18, from the cells C to the spaces C' between the cells, so that upward circulation of air is provided in both said cells and said spaces.

In Figs. 13 and 14 I have shown a method for securing a beam or other transverse structural member to a wall structure containing one or more cellular wall elements, wherein a wall element of the type shown at 2 and provided with two cells C having suitable perforations 18 in the side walls thereof, is preferably employed. A suitable reinforcing rod or the like 61 is passed through the openings 18 in the two adjacent cells, and a beam 62 is entered into the space 63 between the adjacent cells C into engagement with said rod. Said joist may be provided at its lower inner end with an overhang member 64 engaging the rod 61 whereby longitudinal stresses in said joist may be communicated to the wall structure.

In Fig. 14 I have shown the space 63 filled with concrete or other suitable masonry as at 65, whereby a positive interlock is obtained between the beam and the wall structure. Concrete may also be poured in the adjacent cells C to increase the interlock and load distributing ability of the juncture. In this case the rod 61 is securely po-

sitioned against lateral movement, and the beam and concrete block 65 are held immovable in position. It will be understood that a suitable form may be provided along the open side of the space 63 to facilitate the formation of the block 65. This block 65 may be extended downwardly along the element 2 to any desired distance and as many rods as are required may be used to tie the block to the wall element. The blocks may, if desired, be extended downwardly into engagement with a suitable foundation member or the like so that the vertical load imposed by the beam 62 will be communicated to such foundation structure through the concrete column thus provided as well as through the adjacent wall elements.

In Fig. 15 I have shown a construction in which a floor, ceiling or other transverse slab member may be secured to a wall structure 48 provided with one or more metal wall elements having hollow cells C. In this figure I have also shown a wall ventilating construction in which the perforations 18 in the cell side walls are utilized after the manner shown in Fig. 12. The transverse slab member is shown particularly as a floor member, but it will be appreciated that this construction is equally applicable to a ceiling construction or the like. The wall 48 may be assembled of one or more sections of the type shown at 2 or of any of the other types above described, having hollow cells such as C provided with side wall perforations 18, and a rod or pipe 66 is passed through a horizontal series of such perforations and a plurality of reinforcing rods 67 are laid in position bearing on said member 66 and the concrete slab 68 cast in position embedding said rods. The concrete slab will thus surround the side walls of the cells C and will extend into the spaces intermediate adjacent cells. The lower ends of the elements 2 may be suitably secured to a foundation or other member as at 49. This construction provides a simple method whereby a floor slab or the like may be securely interlocked with the wall structure in such manner as to transmit stresses applied in any direction. It will be appreciated that the forms which are utilized for casting the slab 68 may be disposed at substantially any desired vertical angle with respect to the plane of the wall as defined by the elements 2, and thus this construction is applicable in the formation of roofs or other inclined structures.

When it is desired to use the cells C for circulation of air within the wall body, suitable perforations may be provided in the exterior wall of these cells after the manner shown at 47 in Fig. 12, or, if the slab 68 is positioned sufficiently above the foundation member to expose a lower series of perforations 18a, circulatory air may be drawn from below the slab 68 and upwardly into the cells C and thence outwardly through suitable apertures adjacent the upper edge of the wall 48. If plaster or other suitable wall coating material is disposed along the inner face of the wall 48 for example as shown at 51, the space between adjacent cells C will be closed to define an additional cell C' and air will be circulated into this cell C' through an upper series of perforations 18b above the slab 68. It will be appreciated that suitable means will be provided whereby free access of air to the space below the slab 68 will be had if a construction of this type is employed.

In Fig. 16 I have shown a construction in which a plurality of wall elements 2 are secured in load-transmitting relation through the agency of a combined reinforcing rod and masonry construc-

tion. In this figure I have shown three wall sections, 2a, 2b and 2c, the elements 2a and 2b being interlocked through the above-described male and female locking means along the adjacent edges as at 71, and the elements 2b and 2c separated by a masonry structure such as a chimney or the like 72. The element 2a represents one which has been shortened or cut away to provide a window lintel while the sections 2b and 2c may be considered to extend downwardly to a suitable foundation member. In order to provide for full transmission of loads from one element to another, one or more reinforcing rods 73 may be passed through suitable perforations 18, 15 such as above described, in the side walls of the cell portions of the elements 2 and the respective cells filled with concrete or other comparable material as at 70. If desired, before the pouring of the concrete, a series of the perforations 20 18 may be utilized for carrying a service conduit or the like 74 longitudinally of the plane of the wall structure and transverse to the cells thereof, as shown. The rods 73 may be passed through the masonry structure 72 so that the wall becomes in effect a unitary structure and the masonry structure is tied into the wall. In this use it will be found advantageous to provide a suitable plate or the like such as an angle-iron 75 extending along the upper edge portions of the 25 respective wall elements as shown, to which the said elements may be secured in some suitable manner, as by welding at 76.

Under some conditions the cells C will not require a masonry filling, particularly if the vertical load to be sustained by such wall structure is relatively low, in which case, as shown in Fig. 17, the load-transmitting feature is obtained merely by passing the reinforcing rods 73 through the perforations 18 and through the masonry 40 member 72', or bolts 77 employed which may be tightened to position the same and to contribute to the lateral rigidity of the structure.

In Fig. 18 I have shown an isometric view which may represent a portion of a building 45 structure in which many of the related features of the present invention are combined in a single showing. The numeral 80 designates a wall meeting a wall 81 to form a re-entrant angle, and a wall 82 is shown as meeting the wall 81 after 50 the manner of a partition or the like separating adjacent rooms. The junction of the walls 80 and 81 is shown as provided with a masonry reinforcement as at 83 suitably secured to the joining wall elements, after the manner described 55 in my co-pending application for patent on "Metal wall building construction" executed of even date herewith, and the walls 81 and 82 are shown as joined after the manner shown in Fig. 8a of the present application. The walls 80, 81 and 82 are shown as extending below the floor line 60 as defined by the concrete floor slabs 84, 85 and 86 and suitably secured to a masonry foundation member 87. At the left-hand side of the figure I have shown a roof truss or the like 88 mounted at the upper end of the wall 80 and 65 supported on an angle member 89 extending along the upper edge of the wall 80 after the manner of the angle-iron member 75 shown in Fig. 16 and a similar member 89 is provided for the wall 81, extending along the upper edge thereof. It 70 will be appreciated that this roof truss may be secured to the wall after the manner shown in Fig. 13 or Fig. 14 if so desired.

The walls 80, 81 and 82 are shown as formed 75 principally of metal elements of the type shown

at 2 spaced with filler elements 15. At 81 I have shown a masonry column, such as a brick chimney or the like positioned in the wall 81 and secured in stress-communicating relation thereto through the agency of rods 92 extending 5 through a plurality of perforations in the side walls of the respective cells C of the adjacent wall elements 2, after the manner shown in Fig. 16, the respective cells through which the rods 92 extend being filled with concrete or other suitable masonry, as shown at 92', so as to tie the rods 92 to said cells.

At the left of the masonry member 91 I have shown a window 93, the frame of which may be fitted between and suitably secured to the edge 15 portions of adjacent wall elements 2. A suitable window lintel construction is provided by a plurality of shortened wall elements 2a supported with respect to the adjacent wall elements through the agency of a plurality of rods 94 extending through the above-mentioned aligned perforations in the cell side walls after the manner shown in Fig. 16. The several cells through which the rods 94 extend are filled with concrete or other suitable masonry as shown at 94', if desired, so as to provide a unitary wall construction of the desired strength. Immediately below the window 93 the wall elements may consist of flat plates 15a, in view of the fact that no substantial load conditions exist below such a window construction.

The floor slabs 84, 85 and 86 may be secured to the wall elements after the manner shown in Fig. 15 if desired, through the agency of rods or the like 95 and 96 extending through a suitable number of the side wall perforations, upon which may be placed the reinforcing members 97 and 98 and the respective concrete slabs cast thereabout. It will be understood that in most cases a suitable interior coating such as plaster 40 will be provided for the inner surfaces of the various walls as at 99, after the manner shown in Figs. 10 and 11 or in any other desired manner.

Air circulation may be obtained through the 45 wall structure, as described in connection with Fig. 15, if desired, and in this connection, the wall 80, which is formed principally of a plurality of wall elements of the type shown at 2, may take in circulation air through any one or 50 any number of the perforations 18 which are disposed below the slab 84, and this air will pass upwardly through the respective cells C until above said slab, after which it will cross-circulate into the spaces C' between such cells. 55 The member 89 is shown of somewhat less transverse width than the wall elements so that the circulation air may exit from the wall space at the upper ends of the several wall elements, for example through the spaces 101 and 102 60 thus provided at the upper ends of cells C and spaces C' respectively, and thus escape into the roof area.

The above-described forms of building construction are of high structural strength, as will 65 be appreciated by one familiar with the art, and may be obtained at a relatively reasonable cost. It will be seen that a particularly weather-proof and vermin-proof construction is obtained, both due to the character of the construction materials, and the method of construction. The several perforations in the side walls of the wall elements are particularly advantageous both from the standpoint of facilitating the employment of reinforcing media, and from the stand- 70 75

point of providing for extension of service conduits along the walls in the manner described. Numerous modifications of the specific structures herein shown will immediately suggest 5 themselves to one familiar with the art, and the present invention is not to be considered as limited to the present specific disclosure, but rather to the scope defined by the appended claims.

I claim:

- 10 1. In a building construction, a metal wall comprising a plurality of vertical preformed metal wall elements disposed substantially in a vertical plane, at least one of said elements being provided with one or more hollow cells of 15 closed cross section extending substantially the entire length thereof, and said wall including at least two of said hollow cells spaced from one another and each having alined perforations extending through the side walls of said cells 20 transversely of the length thereof, a transverse reinforcing member extending through said perforations and through said two hollow cells and the space therebetween and supported on each of the side walls of said two hollow cells, 25 and a structural member meeting said plane and having a portion extending within said space between said two hollow cells and engaging said reinforcing member in load-transmitting relation thereto.
- 30 2. The construction set forth in claim 1, and comprising in addition: a masonry member disposed within said two cells and the space therebetween, and surrounding said reinforcing member and said extending portion of said structural member.
- 35 3. In a building construction, a metal wall comprising a plurality of vertical preformed metal wall elements disposed in contiguous alined relationship in a substantially vertical plane, certain of said elements being provided with one or more hollow cells of closed cross 40 section extending substantially the entire length thereof and provided with perforations extending through the side walls thereof in a direction 45 transverse to the length of said cells, and a reinforcing member disposed in said perforations and extending through adjacent hollow cells in two or more separate wall elements.
- 45 4. The invention set forth in claim 3 and comprising in addition, means securing said reinforcing member in position in said perforations.
- 50 5. The invention set forth in claim 3, said hollow cells being filled with a structural material positioned to surround said reinforcing member and position the same.
- 55 6. The invention set forth in claim 3, the perforations in the side walls of said hollow cells being positioned in longitudinal alinement with one another in a direction substantially parallel to said plane.
- 60 7. A metal wall building construction comprising two meeting walls each formed of a plurality of preformed metal wall elements disposed in contiguous alined relationship to form a wall, one of said walls being provided with a wall element having a longitudinally extending hollow cell at a position adjacent the junction of said walls and the other of said walls being 65 provided with a wall element having a flat plate portion disposed at the junction of said meeting walls, said flat plate portion providing a space at the junction of said walls of sufficient width to receive said cell of the first-named wall, and 70 means securing said first-named wall to said 75

flat plate portion of said element of said second-named wall.

8. The construction set forth in claim 7, the side walls of the hollow cell of said first-named wall adjacent the junction of said two walls being provided with one or more transverse perforations and said flat plate portion of said second-named wall being provided with one or more perforations in alinement with said first-named perforations, and comprising in addition, 10 a reinforcing member extending through said alined perforations in engagement with both of said walls.

9. The construction set forth in claim 7, the side walls of the hollow cell of said first-named wall adjacent the junction of said two walls being provided with one or more transverse perforations and said flat plate portion of said second-named wall being provided with one or more perforations in alinement with said first-named perforations, and comprising in addition, 15 a reinforcing member extending through said alined perforations in engagement with both of said walls, and a masonry member disposed within said adjacent hollow cell and with said 20 cell-receiving space provided by said flat plate portion.

10. A building construction comprising two meeting walls each formed of a plurality of preformed metal wall elements disposed in contiguous relationship to form a wall, one of said meeting walls being formed of wall elements provided with longitudinally extending hollow cells and the other of said meeting walls being formed of wall elements provided with longitudinally extending hollow cells and a wall element disposed between two adjacent cellular elements, at least a portion of said last-named element consisting of a flat plate providing a space between adjacent elements of sufficient 35 width to receive a hollow cell of the first-named wall, the edge of the first-named wall extending between said adjacent cells of said second-named wall, the walls of said hollow cell of said first-named wall adjacent the junction of said two walls being provided with one or more transverse perforations and the adjacent cells of said second-named wall being provided with one or more perforations in alinement with said first-named perforations, and a reinforcing 40 member extending through said alined perforations in engagement with both of said walls.

11. The construction set forth in claim 10, and comprising in addition; a masonry member disposed within said adjacent hollow cell and within said cell-receiving space provided by said flat plate portion in position to surround at least a portion of said reinforcing member.

12. In a building construction, a metal wall comprising a plurality of preformed metal wall elements disposed in contiguous alined relationship, certain of said elements being provided with one or more hollow cells of closed cross-section extending substantially the entire length thereof, a structural member extending along 65 and secured to the upper ends of said elements in load distributing relation thereto, means supporting the lower ends of said elements and closing said hollow cells, said cells having forward and rearward wall portions extending respectively in separated parallel planes at opposite sides of said wall, a layer of wall surface material disposed in one of said separated parallel planes at one side of the wall and defining additional hollow cells of closed cross-section with 70 75

the walls of said first-mentioned hollow cells, at least some of said elements being provided with a perforation in the wall portion thereof in one of said separated parallel planes for circulation of air between the exterior of said wall and the interior of at least some of said first-mentioned hollow cells, and the walls of said first-mentioned cells being provided with perforations providing lateral communication between said first-mentioned and said additional hollow cells.

13. The invention set forth in claim 12, at least some of said first-mentioned and said additional hollow cells being open at their upper ends adjacent said structural member.

14. In a building construction, a metal wall comprising: a plurality of preformed metal wall elements disposed in contiguous aligned relationship, certain of said elements being provided with one or more hollow cells of closed cross-section extending substantially the entire length thereof; a structural member extending along and secured to the upper ends of said elements in load distributing relation thereto; means supporting the lower ends of said elements and closing said hollow cells; a masonry member meeting the plane of said wall at a level above said lower ends, said cells having forward and rearward wall portions extending respectively in separated parallel planes at opposite sides of said wall and said masonry member extending between said hollow cells; a layer of wall surface material disposed in one of said separated parallel planes at one side of the wall and defining additional hollow cells of closed cross-section with the walls of first-mentioned hollow cells, said additional hollow cells extending upwardly from said masonry member, at least some of said elements being provided with a perforation in the wall portion thereof below said masonry member for circulation of air to the interior of

said first-mentioned hollow cells and the walls of said first-mentioned cells being provided with perforations above said masonry member providing lateral communication between first-mentioned cells and said additional cells.

5

15. In a building construction, a metal wall comprising a plurality of vertical preformed metal wall elements disposed substantially in a vertical plane, a vertically extending masonry member located in the plane of said wall and positioned intermediate the longitudinal length thereof, at least one of said elements at each longitudinal side of said masonry member being provided with one or more hollow cells of closed cross-section extending substantially the vertical length thereof and having a plurality of aligned perforations extending through the side walls of said cells transversely of the vertical length thereof, the perforations in the hollow cells at each longitudinal side of said masonry member being in substantial alignment with one another, a transverse reinforcing member extending longitudinally through said masonry member and through a group of said aligned perforations, and means securing said transverse reinforcing member in position within said perforations.

16. The invention set forth in claim 15, said last-named means including a masonry member disposed within one or more of said hollow cells and engaging such portion of said transverse reinforcing member as lies within said last-mentioned one or more hollow cells.

17. The invention set forth in claim 15, at least one of said hollow cells at each longitudinal side of said masonry member being provided with a masonry member engaging said reinforcing member to position the same with respect to said at least one hollow cell.

GEORGE VINCENT PALMER. 40
